UNITED STATES PATENT OFFICE.

ALFRED L. WEISSENTHANNER, OF BAYONNE, NEW JERSEY.

SEALING APPARATUS FOR JARS, &c.

1,196,915.

Specification of Letters Patent. Patented Sept. 5, 1916.

Application filed February 5, 1912. Serial No. 675,621.

To all whom it may concern:

Be it known that I, ALFRED L. WEISSENTHANNER, a citizen of France, and resident of Bayonne, in the county of Hudson and State of New Jersey, have invented certain new and useful Improvements in Sealing Apparatus for Jars, &c., of which the following is a specification.

This invention relates to apparatus for sealing by the so-called vacuum-process receptacles containing conserved fruits, jellies, and the like. In that process, as is well understood, the receptacle, almost wholly filled with the cooked substance and with the cover loosely applied, is introduced into a closed chamber; air is then exhausted from the chamber to induce a vacuum within the same and the receptacle, and thereupon air is permitted to enter the chamber, the result being that the cover, by virtue of the external atmospheric pressure thereon, is pressed into and maintained in intimate sealing relation with the upper edge of the receptacle.

The object of my invention is to provide a vacuum sealing apparatus of simple and efficient construction and operation, whereby a large number of receptacles can be expeditiously sealed; and to this end my invention, as generally stated, comprises various novel features of construction and organization which will be hereinafter described and claimed.

In the annexed drawings—Figure 1 is a front elevation of a sealing apparatus embodying my invention, the vacuum chest being shown in raised position. Fig. 2 is a side elevation of the apparatus. Fig. 3 is a fragmentary sectional elevation showing the connecting devices between the air-inlet valve of the vacuum chest and the liquid return valve of the hydraulic mechanism. Fig. 4 is a longitudinal vertical section, illustrating the action of the stationary sealing head upon the covers of the receptacles. Fig. 5 is a transverse vertical section, as on the line 5—5 of Fig. 4. Fig. 6 is a sectional detail of a portion of the sealing head showing more clearly the elastic pad thereof. Figs. 7 and 8 are transverse sections through one of the metallic covers showing the contour of the same before and after the action of the sealing head thereon.

1 designates a vertically reciprocable chest of appropriate size and shape which affords a vacuum chamber to receive and contain the receptacles to be sealed. One wall of

the chest is conveniently provided with a hinged door 2 to permit access thereto for the ready insertion and removal of the receptacles; the door being preferably automatically closed as, for example, by the action of a suitably-disposed weighted lever 3. Entering the upper portion of the chest is a pipe 4 which is flexibly connected, as by the hose 5, with a suitable air-exhaust pump (not shown) which is maintained in constant operation. The chest is advantageously equipped with an indicator as 6. A stuffing box 7 in the top of the chest slidingly receives a rigid rod 8 which not only affords a vertical guide for the chest but carries and sustains within the chamber a stationary sealing head. This rod depends from a cross-bar 9 which is sustained by posts 10 rising from a bed 11 supported by appropriate standards 12. Suitably-disposed springs 13 encircling posts 14 rising from the top of the chest serve to maintain the latter normally depressed. The sealing head comprises a metal plate or body 15 furnished on its under side with a pad of elastic practically non-compressible substance composed preferably of a sheet of rubber 16 faced with porous material such as the textile fabric 17. (See Fig. 6.)

As a simple and efficient means to reciprocate the chest, I preferably support it by and upon a piston 18 which is slidingly fitted to a hydraulic cylinder 19 in operative communication with an ordinary hydraulic pump 20, said cylinder being conveniently made an integral part of the bed 11. The piston of the pump is connected by means of a pitman 21 with a crank 22, or the like, on a driven shaft 23 having its bearings in brackets 24 on the cross-bar 9. The pump is connected with the tank 25 and cylinder 19 by usual pipe and valve connections whereby during the operation of the pump liquid is supplied thereto from the tank and forced therefrom to the hydraulic cylinder in such a manner that the piston and its chest are forcibly raised, and whereby the liquid can be diverted from such cylinder to the tank when a predetermined pressure has been exerted upon the piston.

The pipe and valve connections herein illustrated may be briefly described as follows: 26 is an inlet pipe leading from the tank to the lower portion of the pump cylinder and provided with the usual check valve 27; 28 is a discharge pipe leading from

the pump cylinder to the lower portion of the interior of the hydraulic cylinder 19 and provided also with the usual check valve 29, and 30 is a return pipe leading from the 5 interior of the lower part of the hydraulic cylinder to the upper portion of the tank. The return pipe 30 is provided at a suitable point in its length with a return valve 31 which normally interrupts the communication 10 between the cylinder 19 and the tank, said valve being preferably a puppet valve which is yieldingly held to its seat, as by a lever 32 which is pivoted at x and is equipped with an adjustable weight 33. This valve 15 thus constitutes a safety valve which is adjusted to control the maximum pressure exerted by the liquid upon the piston within the hydraulic cylinder; that is to say, when such pressure reaches a prescribed limit the 20 valve is automatically opened thereby, to permit the return of the liquid to the tank. The discharge pipe 28 is provided with an ordinary pressure gage 28^a.

Leading from the top of the vacuum 25 chamber to the open air is a pipe 34 provided with a valve 35 adapted to be opened or closed to permit or check the ingress of air to the chamber, as desired. The stem of this valve is provided with a crank 36 that 30 is connected by means of a link 37 with the inner arm of a hand lever 38 which is fulcrumed on a suitably disposed post 39 on the bed plate 11, so that by manipulation of the lever 38 the valve 35 can be readily 35 opened or closed as desired. The inner arm of the valve lever 32 extends adjacent the lower portion of the link 37 and the latter is conveniently provided with a laterally projecting shoulder, as the pin 40, which 40 overhangs the proximate arm of said lever, so that when the hand lever is operated to pull down the link and open the air-inlet valve 35, the shoulder impinges upon the opposing lever arm to effect the release of 45 the valve 31 from the closing pressure of the weighted lever arm, thus permitting the liquid readily to open the valve 31 and escape to the tank. When the hand lever is lowered to close the air-inlet valve 35 the 50 shoulder is raised from the lever 32 and the safety valve is caused to resume its seat by the action of the weighted arm of the lever 32 upon the stem of the valve.

The general operation of the mechanism 55 above described is as follows: Assuming the chest to be in its normal or down position, the door thereof is opened and a number of receptacles, such as the glasses A with flanged metallic covers a resting loosely 60 upon them, are placed within the vacuum chamber immediately below the stationary sealing head. The door is then closed and the hand lever 38 is operated to close the air valve 35 and permit the safety valve 31 65 to occupy its normal or closing position.

Communication of the chamber with the atmosphere thus being cut off, a vacuum is established within the chamber through the agency of the exhaust pump; and at the same time, on account of the looseness of 70 the covers, the air is exhausted from the respective receptacles. The liquid is forced by the pump from the tank into the hydraulic cylinder through the pipes 26 and 27, thus bodily raising the piston and the 75 chest in such a manner that the covers of the contained receptacles are pressed tightly against the opposing stationary head and brought into intimate sealing contact with the edges of the respective receptacles. The 80 safety valve 31 is so regulated that when a predetermined pressure has been exerted upon the covers the said valve is raised and the liquid is permitted to return from the hydraulic cylinder to the tank through the 85 pipe 30. At this time the lever 38 is manually operated to open the valve 35 to permit the outside air to enter the vacuum chamber, and also to cause the pin 40 to bear upon the lever 32 and relieve the safety valve. 90 Thus the lifting force of the liquid is removed from the piston, and the latter and the chest are permitted to descend and lower the receptacles and their covers from the sealing head; the liquid returning to the 95 tank by way of the pipe 30. The door of the tank is then opened and the sealed receptacles are removed. When the air is admitted to the chamber the action of the atmospheric pressure directly upon the 100 covers maintains them in sealing contact with the receptacles, it being understood, of course, that such pressure is instantly established on the opening of the air-valve before the slow escape of the liquid through the 105 safety-valve has permitted material retraction of the receptacles from the stationary head. The efficiency of the sealing contact is contributed to by the usual elastic packing a' on the undersides of the respective 110 covers; and also by the action upon the covers of the elastic practically non-compressible substance of the sealing head. The pressure of the circular edges of the covers against this substance causes the circumscribed portions of the latter to bulge forcibly upon the tops of the respective covers in a manner to depress the same and draw their peripheral portions into uniform 115 sealing contact with the top edges of the 120 receptacles. In this connection it is to be noted that owing to the ingress of the air to the pores or interstices of the fabric on the acting surface of the rubber, the otherwise liability of the adherence of the metal 125 covers to the rubber is obviated.

In Figs. 7 and 8 the form and condition of one of the covers before and after the depressing action of the sealing head thereon are clearly illustrated.

I claim:

1. In a sealing apparatus, the combination of a vacuum chest and a sealing head therein movable relatively to each other, a cylinder, a piston therein connected with the movable element, means for supplying pressure to the piston in said cylinder, pressure relief means, including a valve, for the cylinder, means for exhausting air from said chest, means, including a valve, for admitting air to said chest, and connections between the two valves whereby they can be simultaneously operated.
2. In a sealing apparatus, the combination of a vacuum chest and a sealing head therein movable relatively to each other, a cylinder, a piston therein connected with the movable element, a pump, a tank, a connection to provide operative communication of the pump with the cylinder and the tank, and the tank, and a connection to provide return communication between the cylinder and the tank, said latter connection including a valve whereby the communication with the tank can be periodically established, of a reciprocable vacuum chest adapted to be actuated by the piston, a stationary sealing head within the chest, an air inlet for the chest, a valve for said inlet, a lever, a link connection between said lever and the air inlet valve, and means whereby when the lever is operated to open said air-inlet valve the first-named valve is relieved to permit the escape of the fluid from the piston to the tank.
3. In a sealing apparatus, the combination with a cylinder, its piston, a pump, a tank, a connection to provide operative communication of the pump with the cylinder and the tank, and the tank, and a connection to provide return communication between the cylinder and the tank, said latter connection including a valve whereby the communication with the tank can be periodically established, of a reciprocable vacuum chest adapted to be actuated by the piston, a stationary sealing head within the chest, an air inlet for the chest, a valve for said inlet, a lever, a link connection between said lever and the air inlet valve, and means whereby when the lever is operated to open said air-inlet valve the first-named valve is relieved to permit the escape of the fluid from the piston to the tank.

Signed at New York in the county of and State of New York this first day of February A. D. 1912.

ALFRED L. WEISSENTHANNER.
